TRAY AND TABLE COMBINATION

William H. Wiggins, 137 Willowdale Ave.,
Willowdale, Ontario, Canada

Filed Mar. 23, 1970, Ser. No. 22,007

Term of patent 14 years

Int. Cl. D6—03

U.S. Cl. D33—14

FIG. 1 is a perspective view of the tray and table combination;

FIG. 2 is a perspective view of the upper parts of the tray and table combination showing the uppermost tray portion of the tray and table combination in exploded relationship to the pedestal supporting structure;

FIG. 3 is a side elevation of the tray and table combination; and

FIG. 4 is a cross section through the outer parts of the upper flared supporting member and the tray portion of the tray and table combination.

I claim:

The ornamental design for a tray and table combination, as shown and described.
